UNITED STATES PATENT OFFICE

159,420

CLOCK OR SIMILAR ARTICLE

Samuel J. Kaufman, New York, N. Y.

Application March 14, 1949, Serial No. 1,389

Term of patent 7 years

(Cl. D42—7)

To all whom it may concern:

Be it known that I, Samuel J. Kaufman, a citizen of the United States, residing at New York city, in the county and State of New York, have invented a new, original, and ornamental Design for a Clock or Similar Article, of which the following is a specification, reference being had to the accompanying drawing, forming a part thereof.

Fig. 1 is a front view of a clock or similar article, showing my new design.

Fig. 2 is a top view thereof.

The dominant feature of the design resides in the portions shown in full lines.

I claim:

The ornamental design for a clock or similar article, substantially as shown and described.

SAMUEL J. KAUFMAN.
